CIRCUIT BREAKER

Humphreys Milliken, Mount Royal, Quebec,
Canada

Application December 2, 1942, Serial No. 467,643

9. Claims. (Cl. 200—148)

This invention relates to circuit breakers for interrupting power currents at high voltage and has particular reference to 3-pole circuit breakers of the gas blast type.

The main object is to provide a generally improved circuit breaker in which the number of component parts and the space occupied by said parts is reduced to a minimum without sacrificing anything in the way of interrupting capacity and speed of operation.

Other objects, advantages and characteristic features of the invention will be more readily understood from the following detailed description taken in connection with the accompanying drawings, in which—

Fig. 1 is a side view of a 3-pole gas blast circuit breaker designed in accordance with my invention.

Fig. 2 is a rear view of the circuit breaker shown in Fig. 1.

Fig. 3 is an enlarged transverse sectional view of one of the interrupter units, the plane of the section being substantially along the line 3—3 of Fig. 2.

Fig. 4 is a transverse sectional view taken substantially along the line 4—4 of Fig. 3.

Fig. 5 is a sectional view taken substantially along the line 5—5 of Fig. 3.

Fig. 6 is a sectional view taken substantially along the line 6—6 of Fig. 5.

The three poles of the circuit breaker shown in Figs. 1 to 6 inclusive are respectively indicated at A, B and C. Each pole includes an arc chute 10 open at both ends, an arc chute enclosing housing 11, an interrupter switch comprising a main movable interrupter blade 12 and an extensible interrupter arm 13 and a load current switch comprising movable switch contact 14 and stationary switch contact 15. The casing 11 of each pole is carried by a hollow insulator 16 which, in turn, is secured to the upper end of a gas blast conduit 17. The conduits 17 of the several poles extend downwardly through the top of a tank 18 and merge together at their lower ends to provide a large diameter valve seat 19 surrounding an orifice 20 common to all of said conduits. A blast valve 23 closes against seat 19 and may be operated in substantially the same manner as the similar blast valve described in my U. S. Patent No. 2,089,286.

In the open position of valve 23 a blast of compressed air is discharged from tank 18 through the blast conduit 17 and arc chute 10 of each pole and serves to extinguish the arcs which are drawn in the several chutes 10 when the inter-

rupter contact blades 12 are separated from the interrupter arms 13 as hereinafter described.

The interrupter blade 12 of each pole is carried by the upper free end of the associated movable load switch contact 14, the lower end of the latter being connected through hinge 38 to circuit breaker terminal 39 mounted on a supporting insulator 40. The several blades 14 are thus mounted for swinging movement relative to the cooperating stationary load-switch contacts 15 which are attached to the housings 11 and connected through conducting structure 67 to the other terminal 61a of the circuit breaker. Each blade 14 is also connected by bracket 43, insulating rod 44 and crank 45 to a common crank shaft 42 to provide simultaneous operation thereof to either a closed-circuit or an open-circuit position. In the present drawings only one blade 14 is shown connected to shaft 42 but it will be understood that identical connections are provided between the remaining blades 14 and said shaft. As indicated in Figure 1, an additional crank 46 on shaft 42 is connected, by rod 47 and crank 48, to a standard control switch 35.

25 A fourth crank 45a is connected by slotted cross-head to a piston rod 54 which extends downwardly through an air cylinder 55 and is secured to a piston 56 working in said cylinder.

The upper end of cylinder 55 is connected to one of the air blast conduits 17 by an air pipe 58. The lower end of the cylinder is connected to tank 18 by an air pipe 59 controlled by a normally closed electrically actuated valve 60. The operating coil (not shown) of valve 60 is connected in circuit with a current source 61 and a normally open manually-operable control switch 62. When switch 62 is closed valve 60 is opened against the resistance of a spring or other suitable biasing means (not shown), which normally serves to hold the valve in its closed position. An exhaust line 63 is connected between cylinder 55 and valve 60. This exhaust line is controlled by a pressure operated valve 64 spring-biased to closed position and to which opening pressure is supplied from pipe 58 through pipe 65. In the open position of valve 64 the air previously supplied to the lower end of cylinder 55 through valve 60 is exhausted to the atmosphere through exhaust line 63.

50 The main interrupter blade 12 comprises an extension 14a of load-switch contact 14 to which is secured a horn portion 12' curved in the arc of a circle centered at the hinge of contact 14. In the closed circuit position of the circuit breaker 55 interrupter blade 12 extends across arc chute 10

and engages the movable interrupter arm 13 which is mounted in a housing 67 attached to casing 11. An opening 68 in the wall of casing 11 fits closely around the horn portion 12' of interrupter blade 12 to minimize leakage of air.

The free end of interrupter blade 12 is provided with a convexly curved surface 12a which is adapted for rolling butt-contact with the complementary concavely curved surface 13a of the movable interrupter arm 13. Arm 13 is mounted for sliding and swinging movement in its housing 67. As here shown arm 13 is provided with a stem 71 which slides through the transverse opening 72 of a hinge member 73, the latter being provided with tubular trunnions 74 mounted in bearing sleeves 75 screwed into threaded openings 76a provided in opposite side walls of housing 67. The stem 71 is encircled by a compression spring 70 which acts against insulating washers 78 and 79 to resist sliding movement of contact 13 in the direction of hinge member 73, said spring being insulated from stem 71 by insulating sleeve 80. The end of stem 71 adjacent to hinge 73 is connected, by flexible conductor 81, to load-circuit terminal 81a. The housing 67 is lined with insulating material 82 so that the only electrical connection between contact 13 and said housing is that afforded by flexible conductor 81. Guide rollers 83 are mounted on opposite ends of a pin 84 extending through contacts 13. These rollers travel along inclined guide ways 85 which are formed by and between separated sections of the insulating material applied to the side walls of housing 67.

When contact 12 is swung to its closed-circuit position extending across the arc chute 10, the convexly curved end 12a of said contact engages the concavely curved end of contact 13 and causes the latter to be swung from the full to the dotted line position shown in Fig. 3. During the downward movement thereof contact 13 is forced to the right against the resistance of spring 76 which serves to maintain the requisite contact pressure between the engaging surfaces of the two contacts.

When contacts 12 and 13 are in the dotted line position shown in Figs. 1 and 3 the free end of contact 12 bears against an insulating block 87 carried by a piston 88 working in cylinder 89, which is carried by and opens into housing 67. The lower closed end of cylinder 89 is provided with a port 90 which is connected by pipe 91 to the blast passage of the adjacent arc chute 10. Piston 88 is normally held at the lower end of cylinder 89 by a spring 92 acting against the enlarged end 93 of piston rod 94.

The operation of the circuit breaker described herein may be described as follows:

In the closed-circuit position of the circuit breaker the air supply valve 27 of tank 18 is open. Tank 18 and pressure chamber 22 are both filled with air under pressure since the leakage port 31 of valve 30 provides restricted communication between air supply conduit 26 and pressure chamber 22. The pressure thus established in chamber 22 is effective to hold the diaphragm or blast valve 23 tightly closed against its seat 24. The interrupter contacts 12 and 13 and the load-switch contacts 14 and 15 of each pole are in the closed-circuit position shown in Fig. 1.

When a fault occurs on the circuit relay contact 36 closes automatically thus energizing the solenoid of valve 33 and causing said valve and blast valve 23 to open, sending a blast of com-

pressed air through the air blast conduit 17 and arc chute 10 of each pole of the circuit breaker. A small portion of the air thus delivered to arc chute 10 passes through pipe 91 into the lower closed end of cylinder 89, exerting upward pressure on piston 88, maintaining pressure on the contacting ends of blade 12 and arm 13, preventing their separation until they have moved about 5" at which time arm 13 strikes the top wall of housing 67 which stops arm 13 instantly, while blade 12 continues its motion, both interrupter contacts having been accelerated to a high velocity before they part, thus minimizing the time required to separate blade 12 from arm 13 by a distance sufficient to prevent "re-striking" of the arc (after momentary interruption) at the instant of current-zero and peak voltage. Many interrupting tests on this design have shown this feature reduces the time of this critical separation to less than $1/8$ of a cycle ($1/400$ of a second).

After contact 12 leaves the piston-carried block 87 the opening motion of said contact is continued by its momentum and by the piston 56 operating in cylinder 55, said piston being forced downwardly by the air blast pressure which is supplied to the upper end of cylinder 55 through pipe 53. At this time the building up of opposing pressure in the lower end of cylinder 55 is prevented by the opening of exhaust valve 64 which is opened by pressure transmitted through branch line 65.

In the opening operation just described, the combined angular motion and radial motion of contact 13 and stem 71 maintains contact with 12 until after blade 14 has moved out of engagement with contact 15, thereby shunting all current to contacts 12 and 13 before they part, drawing an arc which is extinguished by the blast of air.

During the downward movement of the piston 56 the rotation of crankshaft 42 serves, through the connections previously described, to open the mechanically actuated switch 35 thereby de-energizing the solenoid of valve 33 and permitting said valve and blast valve 23 to close.

In the open-circuit position of the circuit breaker the interrupting contacts 12 of the three poles are swung completely out of the arc chute 10 as indicated by dotted lines in Fig. 1.

The re-closing of the circuit breaker is accomplished by closing the manually operable control switch 62 to energize the operating coil of valve 60 which is thus opened to permit flow of air from tank 18 into the lower end of cylinder 55. Piston 56 is thus moved upwardly in cylinder 55 and operates through the agency of crankshaft 42 to cause the three interrupting contacts 12 to be swung back to their closed-circuit position extending across the arc chutes 10 as shown. The piston 88 operating in cylinder 89 is returned to its starting position by spring 92 as soon as the pressure in pipe 91 drops following the re-closing of the air blast valve 23.

My improved circuit breaker, when constructed and operated as described herein, is characterized by a number of important advantageous features. The design and arrangement of the component parts permits the amount of space occupied by the circuit breaker to be substantially reduced by arranging the several poles so that the centers thereof are spaced apart the minimum permissible distance which is approximately 10" center to center. Such close spacing of the poles is made possible by providing a large diameter blast-valve seat 24 and locating said

seat a distance below the several poles which is considerably greater than the distance between the centers of said poles. This permits the use of blast conduits 17 which have a minimum pneumatic resistance; that is to say, conduits which have a minimum change in direction and in which the necessary bends have maximum radius of curvature.

In the closed-circuit position of the circuit breaker the interrupter contacts 12 and 13 of each pole are shunted by the associated load contacts 14 and 15 which are capable of carrying the rated load current.

During the circuit-opening operation of the circuit breaker it is important that the load contacts 14 of the three poles be separated from the load contacts 15 before the interrupter contacts 12 are separated from the contacts 13. It is equally important that, during the circuit-closing operation of the circuit breaker, the interrupter contacts 12 be engaged with the cooperating interrupter contacts 13 before the load contacts 14 are engaged with load contacts 15. These requirements are adequately provided for by the present invention. In this connection it will be noted that, in the circuit-opening operation of the interrupter, the interrupter contacts 12 and 13 remain engaged with each other until the contact 13 has swung upwardly a distance of approximately 5" from the dotted line position shown in Fig. 3. During this 5" movement of the interrupter contact 13 while still engaged with the interrupter contact 12, the load-carrying contact 14 is withdrawn a substantial distance from contact 15 so that, at the time the interrupter contact 12 separates from the interrupter contact 13, there is a sufficient air gap between the contacts 14 and 15 to ensure that no arc is drawn between these contacts which would cause serious damage in the case of a short-circuit current. During the closing operation of the circuit breaker the interrupter contact 12 engages the interrupter contact 13, as indicated by full lines in Fig. 3, before the shunt contact 14 engages the contacts 15. This prevents any danger of arcing or burning at the shunt contacts 14 and 15 during the closing operation of the circuit breaker.

It is important to maintain butt contact between the engaging interrupter contacts 12 and 13 during the travel of these contacts from the full to the dotted line position shown in Fig. 3 and vice versa. When the interrupter contact 13 is mounted as shown in the present drawings the desired butt contact pressure is provided by the springs 76 with a change of only approximately 1 1/2" in the length of the springs during the swinging motion of contacts 13 to and from the full and dotted line position shown in Fig. 3. This is an important feature since it minimizes the length of the spring required and the resulting maximum spring pressure and the force required to close the contacts. A further advantage is that, in the closed position, the spring 76 is on "dead center" and therefore its pressure does not tend to open the circuit breaker.

One of the troubles commonly experienced with interrupter contacts is the accidental welding together of the contacts as they slide against one another while carrying short circuit current thereby interfering with the proper full movement of the interrupter contacts in the next subsequent operation of the circuit breaker. Such interference would, of course, prevent the spring 76 from maintaining proper contact between the

interrupter contacts 12 and 13 so that, in the subsequent opening operation of the circuit breaker, the circuit would be opened by the load-carrying contacts 14 and 15 instead of by the opening movement of the interrupter contacts 12 and 13 and this would result in failure to interrupt the short circuit current. In the circuit breaker described herein this difficulty is avoided by insulating the interrupter contacts 13 from their casings 67 and from their swivel members 73 so that the only electrical connection between the interrupter contact 13 and casing 67 is through the flexible conductor 81 which must therefore carry all of the short circuit current after the load contact 14 has separated from contact 15.

A very desirable rolling type of butt contact is provided between the interrupter contacts 12 and 13 by forming the contact 12 with a convexly curved surface 12a for engagement with the complementary concavely curved surface 13a of contact 13.

If the circuit breaker shown in Figs. 1 to 6 inclusive should close on a short circuit its quick re-opening will not be impeded by the residual closing air in the cylinder 55 since the blast pressure resulting from the opening of blast valve 23 will cause exhaust valve 64 to open so that the residual closing pressure in the lower end of cylinder 55 will be exhausted therefrom and therefore will not impede the prompt opening of the circuit breaker by the blast pressure transmitted to cylinders 55 and 89.

As shown to advantage in Fig. 3, an arcing contact 13b is arranged in the arc chute 10 of each pole at a point adjacent the extreme upper limit of movement of the interrupter contact 13. As the interrupter contact 12 leaves the contact 13 the arc drawn between these contacts is transferred to the arcing contact 13b which is insulated from the interrupter contact 13.

Having thus described what I now conceive to be the preferred embodiment of this invention it will be understood that various modifications may be resorted to within the scope and spirit of the appended claims.

Having thus described my invention, what I claim is:

1. An air blast circuit breaker comprising two terminals, an air blast passage, means for sending a blast of compressed air through said passage, a load current switch, an interrupter switch in shunt with the load current switch when the circuit breaker is fully closed, said interrupter switch comprising a main movable interrupter blade electrically joined to one of said terminals, an extensible interrupter arm electrically joined to the other terminal, means whereby said interrupter blade and arm make and/or break contact when they are in the edge of said air blast passage with the blade positioned across said passage, said blade being hinged at one end adjacent the terminal to which it is electrically joined, said arm being hinged at a point outside of said air passage and having a radial component of motion, said radial component being spring-biased to maintain contact-pressure against said main interrupter blade during a portion of their motion, said radial component of motion being less than the total angular motion of the contact-end of said arm, and pneumatic means co-acting with the biasing spring of said arm to maintain contact between said main interrupter blade and said arm during the first portion of their opening motion.

2. An air blast circuit breaker comprising two terminals, an air blast passage, means for sending a blast of compressed air through said passage, a load current switch, an interrupter switch in shunt with the load current switch when the circuit breaker is fully closed, said interrupter switch comprising a main movable interrupter blade electrically joined to one of said terminals, an extensible interrupter arm electrically joined to the other terminal, means whereby said interrupter blade and arm make and/or break contact when they are in the edge of said air blast passage with the blade positioned across said passage, said blade being hinged at one end adjacent the terminal to which it is electrically joined, said arm being hinged at a point outside of said air passage and having a radial component of motion, said radial component being spring-biased to maintain contact-pressure against said main interrupter blade during a portion of their motion, said radial component of motion being less than the total angular motion of the contact-end of said arm, and pneumatic means co-acting with the biasing spring of said arm to maintain contact between said main interrupter blade and said arm during the first portion of their opening motion until the contact-end of said arm reaches said air blast passage.

3. An air blast circuit breaker comprising two terminals, an air blast passage, means for sending a blast of compressed air through said passage, a load current switch, an interrupter switch in shunt with the load current switch when the circuit breaker is fully closed, said interrupter switch comprising a main movable interrupter blade electrically joined to one of said terminals, an extensible interrupter arm electrically joined to the other terminal, means whereby said interrupter blade and arm make and/or break contact when they are in the edge of said air blast passage with the blade positioned across said passage, said blade being hinged at one end adjacent the terminal to which it is electrically joined, said arm being hinged at a point outside of said air passage and having a radial component of motion, said radial component being spring-biased to maintain contact-pressure against said main interrupter blade during a portion of their motion, said radial component of motion being less than the total angular motion of the contact-end of said arm, pneumatic means co-acting with the biasing spring of said arm to maintain contact between said main interrupter blade and said arm during the first portion of their opening motion until the contact-end of said arm reaches said air blast passage, and means instantly stopping and holding the contact-end of said arm at the edge of said air passage.

4. An air blast circuit breaker comprising two terminals, an air blast passage, means for sending a blast of compressed air through said passage, a load current switch, an interrupter switch in shunt with the load current switch when the circuit breaker is fully closed, said interrupter switch comprising a main movable interrupter blade electrically joined to one of said terminals, an extensible interrupter arm electrically joined to the other terminal, means whereby said interrupter blade and arm make and/or break contact when they are in the edge of said air blast passage with the blade positioned across said passage, said blade being hinged at one end adjacent the terminal to which it is electrically

joined, said arm being hinged at a point outside of said air passage and having a radial component of motion, said radial component being spring-biased to maintain contact-pressure against said main interrupter blade during a portion of their motion, said radial component of motion being less than the total angular motion of the contact-end of said arm, pneumatic means co-acting with the biasing spring of said arm to maintain contact between said main interrupter blade and said arm during the first portion of their opening motion until the contact-end of said arm reaches said air blast passage, means instantly stopping and holding the contact-end of said arm at the edge of said air passage and spring means returning said pneumatic means to its normal position upon cessation of said air blast in said air blast passage.

5. An air blast circuit breaker comprising two terminals, an air blast passage, means for sending a blast of compressed air through said passage, a load current switch, an interrupter switch in shunt with the load current switch when the circuit breaker is fully closed, said interrupter switch comprising a main movable interrupter blade electrically joined to one of said terminals, an extensible interrupter arm electrically joined to the other terminal, means whereby said interrupter blade and arm make and/or break contact when they are in the edge of said air blast passage with the blade positioned across said passage, said blade being hinged at one end adjacent the terminal to which it is electrically joined, said arm being hinged at a point outside of said air passage and having a radial component of motion, said radial component of motion being spring-biased to maintain contact-pressure against said main interrupter blade during a portion of their motion, said extensible arm having a contacting-end shaped to maintain rolling contact with the contacting-end of said main movable interrupter blade.

6. An air blast circuit breaker comprising two terminals, an air blast passage, means for sending a blast of compressed air through said passage, an interrupter switch comprising a main movable interrupter blade electrically joined to one of said terminals, an extensible interrupter arm electrically joined to the other terminal, means whereby said interrupter blade and arm make and/or break contact when they are in the edge of said air blast passage with the blade positioned across said passage, said blade being hinged at one end adjacent the terminal to which it is electrically joined, and said extensible arm being hinged at a point outside of said air blast passage and having a contacting-end concave in profile, spring-biased, and shaped to maintain rolling contact with the contacting-end of said main interrupter blade.

7. A multi-pole air blast circuit breaker in which each pole comprises two terminals, an air blast passage, means for sending a blast of compressed air through said passage, an interrupter switch comprising a main movable interrupter blade hinged at one end, an extensible spring-biased interrupter arm normally in series with said blade, said arm being hinged at one end, means for moving said blade so that its contacting-end moves across said air blast passage, means whereby said blade and arm make and/or break contact when their contacting-ends are at the edge of said air blast passage, means whereby said contacting-ends of said blade and arm move in contact with each other outside of said air

blast passage and pneumatic means co-acting with the biasing spring of said extensible arm to maintain contact between said main interrupter blade and said arm during the first portion of their opening motion.

8. An air blast circuit breaker having an air blast passage, means for sending a blast of compressed air through said passage, a load-current switch, an interrupter switch in shunt with the load current switch when said circuit breaker is fully closed, said interrupter switch comprising a main interrupter switch-blade having a radial portion hinged at one end and a curved portion joined to the other end of said radial portion, said curved portion being shaped to the arc of a circle concentric with the center of said hinged end and having a contact-end, said air blast passage having openings in its walls permitting movement of said curved portion of said blade through said openings and across said air blast passage, a movable and extensible interrupter arm having a contact-end spring-biased to engage the contact-end of said blade, said extensible arm having a hinge rotatable about an axis parallel to the axis of rotation of said main interrupter switch-blade, the perpendicular distance between the two said parallel axes of rotation being greater than the radius of rotation of said curved switch-blade but less than the sum of said radius and the length of said extensible arm when the latter is fully extended by its biasing spring, means whereby said two contact-ends make and/or break contact when they are in the edge of said air blast passage with the curved portion of said switch-blade extending across said air blast passage and pneumatic means co-acting with the biasing spring of said extensible arm to maintain contact between the two said con-

tact-ends during the first portion of the opening motion of said circuit breaker.

9. An air blast circuit breaker having an air blast passage, means for sending a blast of compressed air through said passage, a load-current switch, an interrupter switch in shunt with the load current switch when said circuit breaker is fully closed, said interrupter switch comprising a main interrupter switch-blade having a radial portion hinged at one end and a curved portion joined to the other end of said radial portion, said curved portion being shaped to the arc of a circle concentric with the center of said hinged end and having a contact-end, said air blast passage having openings in its walls permitting movement of said curved portion of said blade through said openings and across said air blast passage, a movable and extensible interrupter arm having a contact-end spring-biased to engage the contact-end of said blade in abutting contact, said extensible arm having a hinge rotatable about an axis parallel to the axis of rotation of said main interrupter switch-blade, the perpendicular distance between the two said parallel axes of rotation being greater than the radius of rotation of said curved switch-blade but less than the sum of said radius and the length of said extensible arm when the latter is fully extended by its biasing spring, means whereby said two contact-ends make and/or break contact when they are in the edge of said air blast passage with the curved portion of said switch-blade extending across said air blast passage and pneumatic means co-acting with the biasing spring of said extensible arm to maintain butting contact between the two said contact-ends during the first portion of the opening motion of said circuit breaker.

HUMPHREYS MILLIKEN.
